UNITED STATES PATENT OFFICE.

EVERETT H. DUNBAR, OF LYNN, MASSACHUSETTS.

SHOE.

1,174,133.

Specification of Letters Patent.

Patented Mar. 7, 1916.

Application filed September 17, 1915. Serial No. 51,223.

To all whom it may concern:

Be it known that I, EVERETT H. DUNBAR, a citizen of the United States, residing at Lynn, in the county of Suffolk and Commonwealth of Massachusetts, have invented 5 a new and useful Improvement in Shoes, of which the following is a specification.

My invention relates to a type of shoe designed for the corrective treatment of the 10 foot, such as the restoration of fallen or "broken" arches, and it has been the special object of my invention to provide a shoe which may accomplish this result without the use of an independent member such as a 15 removable arch support.

It has been the further object of my invention to so design and construct a shoe that the corrective means may be quickly and easily adjustable so that it may be 20 adapted to the particular and varying requirements of the wearer. This I accomplish by means of a pocket in the inner sole provided with an aperture through which padding material may be inserted.

25 My invention may be best understood by reference to the accompanying drawing in which—

Figure I is a top view of the inner sole of the shoe with the padding pocket and its 30 metal support indicated by dotted lines. Fig. II. is a vertical cross section on line 2—2 of Fig. I. Fig. III is a longitudinal cross section of a shoe provided with my device.

35 Referring now more specifically to the drawing A is the inner sole of a shoe provided with the usual sole B and the upper C. Beneath the inner sole is stitched a piece of leather, canvas or other suitable material 40 D, thereby forming a pocket which is indicated by the dotted line d of Fig. I. Entrance may be had to this pocket through the slot d¹ in the inner sole A. It will be apparent to those familiar with the art that 45 this pocket is located beneath the transverse arch which is to be treated in the shoe as illustrated in the drawing but I do not confine myself to a pocket thus located as it is obvious that the pocket may be elsewhere

50 located for the corrective treatment of the longitudinal arch or other parts of the foot. Through the slot or aperture d may readily be inserted by means of a small pair of pliers padding G for which I preferably 55 employ curled horsehair, although wool, cotton or other material may be used, thus

forming a boss or pad which supports the bones of the arch of the foot of the wearer which require corrective re-placement. This pad so formed is preferably supported by a 60 thin plate of steel or other suitable metal E, shape of which is best disclosed by the dotted line e in Fig. I, where it will be seen to be elongated so as to form not only a support for the pad but also the usual shank 65 which is commonly used in shoes although many shoes are now made with a flexible sole which does not include a metallic shank, and it is to be understood that I do not in any way limit my invention so as to include 70 a metallic member of the form indicated. This metallic member E may be provided with holes F through which it may be tacked to the wooden last so that it may be held in place in the process of manufacture. 75

While I have shown in the form of my invention as disclosed in the drawing a pocket formed by stitching the member D to the end side of the sole it will, nevertheless, be apparent that if a very thin and flexible 80 leather or other suitable material be used the pocket might well be formed by applying this member to the upper side of the innersole without departing from the scope of my invention. 85

It will be readily understood from the foregoing that there is formed in the innersole a boss or pad for the corrective treatment of the bones of the foot which is not subject to displacement and which will be 90 sufficiently yielding to be comfortable and which will be capable of change and adaptation to the particular requirements of the wearer. It is also quite possible by similar means to form more than one boss or pad in 95 the innersole when the wearer of my improved shoe requires corrective treatment in more than one part of his foot.

Having thus fully described my invention what I claim is—

1. A shoe having an innersole attached thereto and a pocket in said innersole provided with an aperture in the top thereof through which padding material may be inserted or withdrawn. 100

2. A shoe having an innersole attached thereto, a pocket in said innersole, and padding material in said pocket, said pocket being provided with an aperture in the top thereof through which said padding material may be inserted or withdrawn. 105

3. A shoe having an innersole attached 110

thereto, a pocket in said innersole, padding material in said pocket, said pocket being provided with an aperture in the top thereof through which said padding material may be inserted or withdrawn, and a metal shank in the sole of said shoe, said shank being extended to form a support for said padding.

4. A shoe having an innersole attached thereto, a piece of suitable material fastened

beneath said innersole in a manner whereby a pocket is formed between said innersole and said piece, a slotted aperture in said innersole giving access to said pocket, padding material in said pocket, and a metal shank ¹⁵ in the sole of said shoe, said shank being extended to form a support for the pad formed in said pocket.

EVERETT H. DUNBAR.
